FIG. 4

FIG. 5

FIGURE 1 is a front and right side perspective of a magnetic tape transport, showing our new design;

FIGURE 2 is a right side elevational view, the opposite side being substantially a mirror image thereof;

FIGURE 3 is a back elevation;

FIGURE 4 is a front elevation; and

FIGURE 5 is a front and top view, taken along a line normal to the plane of the top.

The tape reels are shown in broken lines for illustrative purposes only. Portions of the figures are diagonally lined to illustrated transparency. The grill on the back in FIGURE 3 is continuous within the boundaries shown.

The dominant features of our new design have been shown in solid lines in the drawing.

We claim:

The ornamental design for a magnetic tape transport, substantially as shown and described.
